UNITED STATES PATENT OFFICE.

GEORGE H. GILBERT, OF GERMANTOWN, PENNSYLVANIA.

MANUFACTURE OF HOSIERY.

No. 576,797.

Specification of Letters Patent.

Patented Jan. 14, 1902.

Application filed August 27, 1901. Serial No. 322,132.

To all whom it may concern:

Be it known that I, GEORGE H. GILBERT, a citizen of the United States, residing at Germantown, in the county of Philadelphia and State of Pennsylvania, have invented certain new and useful Improvements in Manufacture of Hosiery; and I do hereby declare the following to be a full, clear, and exact description of the invention, such as will enable others skilled in the art to which it appertains to make and use the same.

My present invention relates to the class of hosiery and has for its object the providing of colored stockings of all kinds with an uncolored interior surface or for such portion of the surface as comes in contact with the foot with the greatest pressure.

It has been claimed by many that colored stockings have often been the cause of blood poisoning, especially in cases where for any cause the skin of the foot of the wearer has become abraded. In order to guard against this, stockings having entirely white feet have been made and put on the market. There also have been stockings made in which the heel, bottom of the foot and toe of the stocking have been made of white or uncolored yarn. It has also been proposed to make stockings that shall be free from this objection by knitting the portion desired of two threads, one of the color desired and the other a white thread and plaiting the white thread on the inside of the foot or heel, bottom of the foot and toe. These various forms of stockings are each open to objection in one way or another. The white foot and the white heel, sole and toe are objectionable as the white often becomes stained and discolored from contact with the leather of the shoe and becomes unsightly. The plaited stocking is also open to the objection that the plaited portion of the stocking is never of the full color of the main body of the stocking, such portion having a mottled appearance, composed of a blending of the colors of the plaited yarns. In such cases the white thread is more or less visible from the outside and the whole of the outside of the stocking is not of the uniform color desired.

By my invention I obviate these objections and produce a stocking which has the desired uniform color on the exterior and yet has a

white interior surface for the entire foot or such portion of the same as is desired. This stocking can be made in several ways. The stocking can be full dyed and then turned and the color on the inside to the extent desired discharged by a suitable discharge medium, or a stocking knit of colored yarn can have the surface on the inside to the extent desired discharged of coloring matter and restored to its original color.

The stocking can be knit of white material and then such parts of the interior surface as it is desired to have remain white, may be printed with what is known as a "resist" and the stocking then dyed, or the exterior of the stocking may be colored by printing after the manner of printing calicoes.

I do not limit myself to any particular form or pattern of stocking as my invention can be applied to any stocking without regard to its form or mode of manufacture.

In the drawings, Figure 1 shows the exterior of one of my improved stockings. Fig. 2 is a view of the stocking turned, or the interior surface of the same, and Fig. 3 is a view of the interior of a modified form.

In Fig. 2 the inner surface of the entire foot is uncolored and in Fig. 3 the heel, sole and toe alone are white. I do not, however, limit myself to making the interior of the foot white alone, but may make the whole interior surface without other color.

While I have here considered the stocking to which my invention is applied as having its exterior of one solid color, my invention can be applied to stockings that are striped or parti-colored. The leg and foot may be of different colors or the leg striped and the foot of a solid color, or the leg of a solid color and the foot striped.

I desire to be protected in the application of my invention to all stockings that are made to have a complete and definite scheme of coloring on the exterior thereof, whether uniform throughout or irregular.

What I claim and desire to secure by Letters Patent is:—

1. A stocking composed of a single knitted web having a complete color scheme covering the entire exterior thereof, and an uncolored surface on the interior of the same, substantially as described.

2. A stocking composed of a single knitted web having a complete color scheme covering the entire exterior of the stocking and having an uncolored surface on the interior of the 5 foot, substantially as described.

3. A stocking composed of a single knitted web having a complete color scheme covering the entire exterior of the stocking and having the heel, sole and toe provided with an uncol-

ored interior surface, substantially as de- 10 scribed.

In testimony whereof I affix my signature, in the presence of two witnesses.

GEORGE H. GILBERT.
